US00D842952S

(12) **United States Design Patent** (10) Patent No.: **US D842,952 S**
(45) Date of Patent: **** Mar. 12, 2019**

(54) **GOLF CLUB HEAD**

(71) Applicant: **PARSONS XTREME GOLF, LLC**,
Scottsdale, AZ (US)

(72) Inventors: **Bradley D. Schweigert**, Anthem, AZ
(US); **Caleb S. Kroloff**, Phoenix, AZ
(US)

(73) Assignee: **PARSONS XTREME GOLF, LLC**,
Scottsdale, AZ (US)

(**) Term: **15 Years**

(21) Appl. No.: **29/611,170**

(22) Filed: **Jul. 19, 2017**

Related U.S. Application Data

(63) Continuation-in-part of application No. 29/608,191,
filed on Jun. 20, 2017, now abandoned.

(51) LOC (11) Cl. **21-02**

(52) U.S. Cl.
USPC **D21/743**

(57) CLAIM

The ornamental design for a golf club head, as shown and described.

DESCRIPTION

FIG. 1 is a top perspective view of a golf club head; FIG. 2 is a bottom perspective view of the golf club head of FIG. 1; FIG. 3 is a front elevational view of the golf club head of FIG. 1; FIG. 4 is a rear elevational view of the golf club head of FIG. 1; FIG. 5 is a top view of the golf club head of FIG. 1; FIG. 6 is a bottom view of the golf club head of FIG. 1; FIG. 7 is a left side view of the golf club head of FIG. 1; FIG. 8 is a right side view of the golf club head of FIG. 1; FIG. 9 is a top perspective view of a second embodiment of a golf club head; FIG. 10 is a bottom perspective view of the golf club head of FIG. 9; FIG. 11 is a front elevational view of the golf club head of FIG. 9; FIG. 12 is a rear elevational view of the golf club head of FIG. 9; FIG. 13 is a top view of the golf club head of FIG. 9; FIG. 14 is a bottom view of the golf club head of FIG. 9; FIG. 15 is a left side view of the golf club head of FIG. 9;

FIG. 16 is a right side view of the golf club head of FIG. 9;
FIG. 17 is a top perspective view of a third embodiment of
a golf club head;
FIG. 18 is a bottom perspective view of the golf club head
of FIG. 17;
FIG. 19 is a front elevational view of the golf club head of
FIG. 17;
FIG. 20 is a rear elevational view of the golf club head of
FIG. 17;
FIG. 21 is a top view of the golf club head of FIG. 17;
FIG. 22 is a bottom view of the golf club head of FIG. 17;
FIG. 23 is a left side view of the golf club head of FIG. 17;
and,
FIG. 24 is a right side view of the golf club head of FIG. 17.
The broken lines disclosed on the drawing views are
included for the purpose of illustrating unclaimed subject
matter and forms no part of the claimed design.
